UNITED STATES PATENT OFFICE

125,298

DESIGN FOR A COMBINED HAT AND TIE RACK

Frederick J. Vogt, Grand Rapids, Mich., assignor to Knape & Vogt Manufacturing Company, Grand Rapids, Mich., a corporation of Michigan

Application September 23, 1940, Serial No. 95,289

Term of patent 7 years

To all whom it may concern:

Be it known that I, Frederick J. Vogt, a citizen of the United States, residing at Grand Rapids, in the county of Kent and State of Michigan, have invented a new, original, and ornamental Design for a Combined Hat and Tie Rack, of which the following is a specification, reference being had to the accompanying drawing, forming part thereof.

The figure is a perspective view of a combined hat and tie rack showing my new design.

I claim:

The ornamental design for a combined hat and tie rack, as shown.

FREDERICK J. VOGT.
